The present invention relates to a magnetic device comprising at least one magnetic element having at least two stable conditions which are determined in association with at least one magnetizing source having two possible output conditions.

A magnetic stable device of this general type is disclosed in U.S. Patent 2,770,796 (H. Boer), granted Nov. 13, 1956, wherein the magnetic element is one which is normally not magnetized and which is subjected to the field produced by said magnetizing source in order to register, by the magnetization produced therein, the condition of the magnetizing source. Such magnetization, however, requires a relatively large magnetic field by virtue of the absence of physical contact between the magnetizing source and the magnetic element, and also due to the high impedance presented by the latter to the magnetic energy of the former.

It is therefore an object of the present invention to provide a magnetic device of the above type wherein the condition of a relatively weak magnetizing source can be reliably registered in said magnetic element.

The present magnetic device is characterized by the provision of a magnetic element which is mounted for rotation. This element is a permanent magnet having $2m (m \geq 1)$ poles, which, when moved into proximity to said magnetizing source in one or the other source condition, is either angularly displaced or remains stationary so that the part thereof which is nearest to said magnetizing source exhibits a pole having a polarity opposite the one exhibited by the proximate part of said magnetizing source. The device further includes holding means adapted to coact with said magnetic element for maintaining the latter in predetermined angular positions.

The present magnetic device is also characterized in that said holding means comprises an auxiliary element which is a permanent magnet having $2m (m \geq 1)$ poles and which is rotatably mounted in close proximity to the main magnetic element.

One advantage of such devices is that they have a more universal range of application. Foremost however, as in the above-mentioned U.S. Patent 2,770,796, the present devices are most advantageously applied to arrangements wherein code indications registered by the magnetic elements therein are conveyed between different locations.

The present control system, to be disclosed herewith, employs magnetic devices of the above described type and features coding means each of which comprises a magnetizing source having two possible conditions and each coacting with pairs of main and auxiliary permanent magnet elements, each having $2m (m \geq 1)$ poles which are rotatably mounted in close proximity to each other. Upon a magnetic register element being coupled to a magnetizing source, the main and auxiliary permanent magnets constituting a magnetic register element are either both angularly displaced, or both remain stationary, whereby the part of the main permanent magnet which is nearest to said magnetizing source exhibits a pole having a polarity which is opposed to the one exhibited by the nearest pole of said magnetizing source.

The above mentioned and other objects and features of the invention will become more apparent and the invention itself will be best understood by referring to

the following description of embodiments taken in conjunction with the accompanying drawings in which:

FIG. 1 represents a magnetic bistable device according to the invention;

FIG. 2 shows a detecting means included in a control system according to the invention;

FIG. 3 represents a control system according to the invention.

Principally referring to FIG. 1 the present magnetic bistable device includes a magnetizing source 1 and two annular permanent magnets 2 and 3. The magnetizing source 1 includes a core 4 on which is wound a winding 5 which is coupled to a DC source 6 via change-over contacts 7 and 8. The main and auxiliary magnetic elements 2 and 3 respectively, are supported by and freely rotatable about the rigid wires 9 and 10 which pass through their respective centers. The change-over contacts 7 and 8 form part of a manually operable key (not shown) which has two stable positions, namely a rest position wherein the contacts 7, 8 are in the position shown in FIG. 1 and an operative position wherein these contacts are in the opposite work position. In the following discussion it is assumed for reference purposes that, in the rest position of the not shown key, the core 4 is so magnetized that its lower end exhibits a north pole.

Each of the magnetic elements 2, 3, may have $2m$ poles, where m is any integer greater than zero, but in the following it is assumed that only two-pole elements are employed, one radial half of the element forming one pole and the other radial half constituting the other pole.

It should further be observed that the magnetic elements 2, 3 of each couple of such elements are closely mounted next to each other so that under static, or stable, conditions, facing poles thereof are necessarily of opposite, or attracting, polarities, since poles of like polarity would tend to repel each other and thereby tend to produce a rotation of the elements.

The above magnetic bistable device operates as follows. Suppose that the main and auxiliary magnetic elements 2, 3 are in the positions shown i.e. both have their south pole directed towards the core 4. The south pole of the magnetic element 2 is then strongly attracted by the north pole at the lower edge of core 4 when the contacts 7, 8 are in the normal rest position. When an operator sets the above-mentioned key to the active position, the contacts 7, 8 travel to their active positions and due to this the core 4 is magnetized so as to exhibit a south pole at its lower end. This south pole tends to repel the south pole of the magnetic element 2 and the latter, being freely rotatable, tends to pivot about the rigid wire 9 in the sense indicated. This rotation will however be counteracted by the attractive force existing between the north pole of the main magnetic element 2 and the south pole of the auxiliary magnetic pole element 3. The magnetizing source 1 and the magnetic elements are so chosen that, notwithstanding the action of the auxiliary magnetic element 3, the chain magnetic element 2 starts to pivot and as the south pole of the main magnetic element 2 approaches the south pole of the auxiliary magnetic element 3, the latter will be repelled and will start pivoting in the sense indicated. Finally the main and auxiliary magnetic elements 2, 3 will come to rest in a position wherein the north poles of both elements are directed towards the active south pole of core 4 of the magnetizing source 1.

From the above it follows that, depending upon the position of the not shown key mentioned above, and hence of the change-over contacts 7, 8 controlled by that key, the couple of magnetic elements 2, 3 can be set to one of two stable conditions. It may also be noted that the condition of the magnetizing source remains stably regis-

tered in the associated couple of magnetic elements when the latter are moved out of the range of influence of the former. Should the source be in the 0-condition when the magnetic elements are coupled thereto, the magnetic elements are also set to the 0-condition, their south poles being directed towards the core 4 of the source. On the other hand, if the source is in the 1-condition, the contacts 7, 8 being then in their active positions, the magnetic elements are also set to the 1-condition, their north poles being directed towards the core 4 of the source.

As explained above, the auxiliary magnetic element 3 initially impedes the rotation of the main magnetic element 2 and then rotates therewith. Hence this auxiliary magnetic element 3 constitutes a holding means for the main magnetic element and prevents the latter from pivoting from the 0-position to the 1-position under the influence of forces other than those produced by the magnetizing source 1. If the main magnetic element has 2 poles and is subjected to such an extraneous force, the element will be set to a new condition only if the extraneous force causes the element to undergo a rotational displacement of 180°. For an element having 4 poles this safety margin would become equal to 90°, etc. i.e. the safety margin becomes smaller as the number of poles is increased.

As may be seen with reference to FIG. 1, the plane A—A passing through the centers of the stationary magnetic elements 2, 3 should not be aligned with the extension of the median plane B—B through the core 4, since, in the latter case, the magnetic force vector resulting from the fields produced by the magnetizing source 1 and the magnetic element 2 passes through the center of the element 2 and would hence not produce a torque to pivot the latter.

Obviously such a precaution is not necessary if the magnetic elements 2, 3 are moved relative to the magnetizing source 1, in which event there are a plurality of positions wherein the above resultant magnetic force vector does not pass through the center of the magnetic element 2, and an element in the 0-state will always tend to pivot to the 1-state when the switch is in the active position.

Principally referring to FIG. 2, there is shown a detecting means for detecting the condition which has previously been registered in the magnetic elements 2, 3. This detecting means is constituted by a reed switch comprising contacts 11—12 which is mounted in a sealed envelope 13 and close to which is mounted a permanent magnet 14 which exhibits north and south poles at its upper and lower ends respectively, this south pole facing the upper part of the reed 11. The attraction force produced by the magnetic field of the permanent magnet in the gap where the reeds 11 and 12 face each other is supposed to be insufficient to realize the contact between these reeds. Due to this, the contacts 11—12 is normally open and it may be said that the permanent magnet polarizes the reed switch 13 in a predetermined or 0-condition.

When a couple of magnetic elements 2, 3 which are in the 0-condition, i.e. with their south poles directed towards the reed switch 13, is operatively associated with this reed switch, the latter will not be closed. Indeed, the force produced in the above gap by the magnetic field of the magnetic element 2 is opposite to that produced in this gap by the magnetic field of the permanent magnet 14 and is supposed not to be sufficiently strong to create an inverse field large enough to produce an attraction force between the reeds 11—12 to bring them into contact with each other.

On the contrary, when this couple of magnetic elements 2, 3 is in the 1-condition, i.e. with their north poles directed towards the reed switch 13 as shown, the attraction force produced in the above gap by the magnetic field of the magnetic element 2 acts in the same sense as the force produced in this gap by the magnetic field of the permanent magnet 14. It is supposed that this sum of forces is

sufficient to attract the reeds 11 and 12, thus closing the reed switch.

It should be noted that the reed switch is preferably of the wetted contact type, such a type permitting an extremely high number of operations before it begins to deteriorate.

In a preferred embodiment, the magnetizing sources 1 and the magnetic elements 2, 3 are disposed as shown in FIG. 1 and conveying means are provided for displacing these elements towards detecting means such as shown in FIG. 2 along a horizontal plane a—a which is perpendicular to the median plane B—B of the core, or along a cylindrical surface.

In the United States Patent No. 2,873,863, granted Feb. 17, 1959 to G. X. Lens, a control system is described in which a plurality of code registers are mounted on an endless main conveyor, for the purpose of conveying code signals from a fixed mechanism, operated from an operator's keyboard, to control conveying and sorting apparatus. Therein an intermediate endless conveyor is interposed, at each input station, between the fixed mechanism and the main conveyor. This intermediate conveyor is provided with one or more intermediate registers regularly spaced, which transfer the code indication of the fixed mechanism to the registers on the main conveyor. The auxiliary conveyor permits the fixed mechanism to register a given code during a time substantially independent of the number of inputs. In other words, the maximum coding time is given to the operator controlling the keyboard.

The code registers on the main conveyor and the intermediate code registers are mechanically operated, so that they are subjected to wear. Another disadvantage of this known control system is that it requires a mechanism having an epicyclic pattern of movement, on which are mounted the intermediate registers, for subjecting the latter to a translation movement only and for ensuring a proper cooperation with the registers on the main conveyor for the transfer of the registered code.

The above described magnetic bistable device and detecting means may advantageously be used in a control system of the type disclosed in the above Patent 2,873,863. This will become clear from what follows, reference being had, for this purpose, to FIG. 3 which shows a main conveyor 15, a number of code registers 16, an intermediate register 17, a coding circuit 18 which is operated from an operator's keyboard (not shown) and a detecting station 19.

It is, for instance, supposed that an operator is required to direct the sorting of goods, e.g. letters, to one of 1000 possible destinations numbered 0 to 999. Therefore the keyboard of the operator's stage comprises three sets each having ten keys, these sets of ten keys being used for selectively recording the respective units, tens and hundreds digits of a destination.

It is further supposed that each destination is to be translated in a 2-out-of-5 binary code. Therefore each key controls two out of five pairs of change-over contacts, each such pair constituting part of a magnetizing source of the type shown in FIG. 1. In other words, each key is able to set two out of five magnetizing sources to the 1-condition. To each set of ten keys are associated a set of five magnetizing sources, and each key of a set controls a different pair of magnetizing sources of the associated set according to the above 2-out-of-5 binary code. The three sets of five magnetizing sources, of which only one source is shown, are mounted next to each other above and transversely with respect to the direction of movement of the conveyor 15.

The intermediate conveyor 17 comprises a drum 20 which is rotatable about an axis 21 in the direction shown and which carries a number of pairs of rigid wires such as 22, 23, this number being equal to the number of operators. The wires 22, 23 extend parallel to the rotation axis 21 of the drum which is parallel to the conveyor 15 and perpendicular to the direction of displacement thereof.

On each of the wires 22, 23 are threaded three sets of five magnetic elements such as 24, 25, the elements 24 being the main ones and the elements 25 being auxiliary or holding ones. The threaded magnetic elements are all identical and may for instance have a diameter of 20 mm., and a spacing between successive elements, on the same wire, on the order of 25 mm.

On the main conveyor 15 is mounted a support 26 carrying a plurality of parallel rigid wires such as 27, 28 which are situated parallel to the conveyor 15 and which extend transversely thereto. On each of the wires 27, 28 are threaded three sets each including five magnetic element such as 29, 30, elements 29 being the main ones and elements 30 being the auxiliary or holding ones. These magnetic elements may for instance each have a diameter of 12 mm., with a spacing of .25 mm. between successive elements on any wire, and with a separation between successive wires 27, of 40 mm.

The detecting station 19 includes 1000 groups of detecting means, each such group being disposed above and transversely with respect to the conveyor 15. Each group of detecting means comprises three pairs of reed switches of the type shown in FIG. 2 which are positioned so as to respond simultaneously to the three particular pairs of code bits which characterize the corresponding destination as manifested by the elements 29 on the main conveyor 15. The six reed switch contacts such as 11, 12 of each of the 1000 groups are connected in series with the winding of a corresponding one of 1000 electromagnets 31, across the poles of a DC source (not shown). In this manner the electromagnet 31 will be operated only if all six reed switches in series with its winding have been operated simultaneously, and this occurs only when the associated code signal combination is applied to the reed switches.

The operation of the control system shown in FIG. 3 is as follows. Upon an operator having read a particular destination, he operates three keys in the above-noted keyboard, namely one each in the units, tens and hundreds sets of keys. Due to this, six magnetizing sources in the associated group of 15 magnetizing sources are set to the 1-condition. Hence, when an intermediate register, i.e. a row of 15 magnetic elements such as 24, is rotated towards the row of magnetizing sources, six of the magnetic elements will be set to the 1-condition in the manner described in relation to FIG. 1. In this 1-condition, the north poles of the six selected elements are directed towards the lower poles of the activating magnetizing sources. As the drum continues rotating all of the elements remain fixed in position due to the interlocking action between each couple of elements 24, 25.

When the above row of 15 magnetic elements, having six elements selectively set to the 1-condition, now approaches a row of 15 magnetic elements 29 of a register on the main conveyor 15, six corresponding elements of the latter register will assume the 1-condition in a manner analogous to that described in relation to FIG. 1 on condition that the magnetic forces exerted by the elements 24, 25 are greater than those exerted by the elements 29, 30. In the 1-condition, the north poles of the latter six elements are directed upwardly. When the magnetic elements of the register on the main conveyor are finally passed under the 1000 groups of reed switches of the detecting station, it is clear that one and only one of these groups will have all of its reed contacts simultaneously operated. Hence the electromagnet 31 associated to this group, which controls the sorting transfer of a conveyed article to a particular output destination, will be energized.

From the above it follows that in the control system of FIG. 3 the transfer of codes is performed without frictional mechanical contact so that in comparison to the control system of the Belgian Patent 552,139 the wear is considerably reduced. Also the endless intermediate conveyor need only be given a circular motion instead of an epicyclic one.

While the principles of the invention have been described in connection with specific apparatus, it is to be clearly understood that this description is made only by way of example and not as a limitation on the scope of my invention.

I claim:

1. A magnetic device comprising a permanent magnetic element having at least two poles, a magnetic source having two possible conditions of magnetization, means supporting said element for rotation relative to a given axial reference on said supporting means, further supporting means supporting said element and said supporting means for coupling said element to said magnetizing source to situate said element in an angular position determined by the state of magnetization of said source, and holding means mounted on said further supporting means for cooperating with said magnetic element to stably retain the latter in said position determined by said source, said holding means comprising an auxiliary rotatably mounted magnetic element which is a permanent magnet having at least two poles and which is mounted in close proximity to the main magnetic element.
2. Magnetic bistable device as claimed in claim 1, characterized in that said main and auxiliary permanent magnets are identical.
3. Magnetic bistable device as claimed in claim 1, characterized in that said magnetizing source and said magnetic element are so disposed with respect to each other that the magnetic force vector which results from the fields produced by said magnetizing source and said magnetic element is not confined to the center of said magnetic element.
4. Control system, for registering and detecting information, comprising one or more sets of fixedly mounted coding means for coding information, a plurality of sets of magnetic register elements mounted for cooperation with said sets of coding means, one or more sets of fixedly mounted detecting means including a contact which is polarized by means of a permanent magnet for detecting the thus coded information, and conveying means for conveying said magnetic register elements from said coding means towards said detecting means, each of said coding means comprising a magnetizing source having two possible conditions, each of said magnetic register elements comprising a magnetic couple including rotatably mounted main and auxiliary permanent magnets, each having at least two poles which are mounted in close proximity to each other, and each said magnetic register element being effective, when operatively associated with one of said magnetizing sources, to assume a corresponding condition in which the main and auxiliary magnets thereof are both either angularly displaced to a new position or fixed in position, whereby the polarity of the pole of the main permanent magnet which is nearest to a pole of said magnetizing source is opposed to the polarity of said nearest pole of said magnetizing source.

5. Control system as claimed in claim 4, characterized in that it comprises a main conveyor constituting said conveying means, that each of said sets of magnetic register elements constitutes a code register, that the code registers corresponding to the sets of fixedly mounted coding means are regularly spaced and interlaced in such a way that the distance between two code registers which successively receive information from the same set of coding means is

equal to the distance between successive code registers multiplied by the number of sets of coding means,
 that an intermediate endless conveyor is interposed between each set of coding means and said main conveyor, this intermediate conveyor being provided with one or more intermediate code registers regularly spaced, which register the code of the coding means to transfer it to said code registers on said main conveyor, the motion of the auxiliary conveyor being synchronized with that of the main conveyor so that each intermediate code register cooperates with a corresponding code register on said main conveyor.

6. Control system as claimed in claim 5, characterized in that driving means are provided for imparting to said intermediate conveyor a circular motion.

7. Control system as claimed in claim 5, characterized in that the main and auxiliary permanent magnets, included in said main and intermediae code registers are identical and that the main and auxiliary permanent magnets included in said intermediate code registers are larger than those included in said main code registers.
